Primary Examiner — Ricky Pham(74) *Attorney, Agent, or Firm* — Drinker Biddle & Reath LLP**(57) CLAIM**

The ornamental design for a backrest of a chair, as shown and described.

DESCRIPTION

FIG. 1 is a front perspective view of a backrest of a chair;
 FIG. 2 is a rear perspective view thereof;
 FIG. 3 is a front view thereof;
 FIG. 4 is a rear view thereof;
 FIG. 5 is a right side view thereof, a left side view being a mirror image;
 FIG. 6 is a top plan view thereof;
 FIG. 7 is a bottom view thereof; and,
 FIG. 8 is a partially enlarged view of area 80 in FIG. 3.
 The broken line showing of the backrest of a chair is for the purpose of illustrating environmental structure and forms no part of the claimed design.

1 Claim, 8 Drawing Sheets---
